UNITED STATES PATENT OFFICE

JAMES D. KRIEVE, OF ST. LOUIS, MISSOURI, ASSIGNOR TO INTERNATIONAL SHOE COMPANY, OF ST. LOUIS, MISSOURI, A CORPORATION OF DELAWARE

TREEING JACK

Application filed October 21, 1929. Serial No. 401,056.

This invention relates to treeing jacks for shoes; and an object of the invention is to provide an improved machine for use in finishing shoes while the original last remains in the shoes during the finishing operations.

Another object of the invention is to provide a machine of the character mentioned having a member constructed and arranged to engage within a socket in the shoe last while the shoe remains on the last and to support the shoe in a relationship in which the shoe may be turned about the axis of said member and finished.

Another object of the invention is to provide a machine of the character mentioned having means for adapting the machine for use in supporting shoes having low uppers or for supporting shoes having high uppers, as desired. For supporting high uppers the machine is equipped with means for expanding and smoothing the upper in proper condition for finishing operations.

Another object of the invention is to provide an improved treeing jack capable of the advantageous uses and applications herein disclosed, reference being made to the accompanying drawings, in which

Fig. 1 is a side elevation of my improved machine adapted to support a shoe having a low upper, parts being in section.

Fig. 2 is a vertical longitudinal sectional view of the upper end portion of the machine, showing the arrangement of the devices that are operated to obtain gripping engagement in the socket of a shoe last.

Fig. 3 is a cross sectional view on the line 3—3 of Fig. 2, showing the device for rotatively securing the support for the shoe last in connection with the upper end of the frame.

Fig. 4 is a detailed view showing the gripping device that engages in and grips the wall of the socket of the shoe last to support the same.

Fig. 5 is an outer end elevation of the device that operates to obtain gripping engagement with the wall of the socket of the shoe last.

Fig. 6 is a side elevation of the upper end

of the machine equipped with the devices for expanding and smoothing the high uppers of shoes.

Fig. 7 is a side elevation, slightly enlarged with respect to Fig. 6, showing the devices in the position they occupy when expanding a high upper of a shoe.

Fig. 8 is a side elevation similar to Fig. 7 showing the same devices with one of the expanding members removed.

Fig. 9 is a longitudinal sectional view of the expanding members and their associated parts.

Fig. 10 is a cross sectional view approximately on the line 10—10 of Fig. 8.

Fig. 11 is a lateral side elevation of the movable expanding member.

Fig. 12 is an inner side elevation of the same movable expanding member.

The embodiments of the machine shown comprise a base 1 having rigid therewith a vertical tubular standard 2 which has a vertical split 3 at its upper end so as to permit the upper end of the standard to be expanded and contracted.

A frame member is mounted on the upper end of the standard 2 and comprises a tubular body 4 in rigid connection with a laterally extended arm 5. The arm 5 is designed and adapted to be inserted in and withdrawn from the upper end of the standard 2. The standard 2 at one side of the split 3 is formed with a boss 6 (Fig. 1) and the opposite side of said split 3 is formed with a boss 7 (Fig. 6). The boss 6 has therethrough a hole having a smooth wall and the boss 7 has therethrough a hole having a threaded wall. These bosses support a clamping device which is operative to contract and clamp the upper end of the standard 2

about and against the arm 5 so as to hold said arm 5 and thereby the tubular body 4 in rigid relationship to the standard 2. And, the clamp device may be operated to permit the upper end of the standard to spread to its original position to permit insertion or withdrawal of the arm 5 from the upper end of the standard. The clamping device comprises a stem 8 journaled in the smooth hole in the boss 6 and screwed into the threaded

hole in the boss 7. The stem 8 has rigid therewith adjacent to the boss 6 a head and arm 9 which abuts against the outer surface of the boss 6 so that when the stem 8 is turned 5 by operation of the arm 9, said stem will operate to contract the upper end of the standard 2 or permit the standard to expand, depending upon the direction in which the stem 8 is turned. The arm 9 constitutes a handle 10 for turning the stem 8 for these purposes.

The forward end of the tubular body 4 has mounted therein a member comprising a part 15 of the mechanism whereby the lasted shoe is supported for finishing operations. This member includes a solid cylindrical portion 10 rotative within the forward end of the tubular body 1 and having an abutment shoulder 11 arranged to bear against the forward end of said body 4 to limit extent of 20 movement of this supporting member into said body 4. Forwardly beyond the shoulder 11, this member is formed with a socket 12 designed and adapted to receive another machine part. And the socket 12 has mounted 25 in the wall thereof a set screw 13 operative to clamp against and to release the machine part that is engaged in the socket. The part 10 of this member is formed with a circumferential groove 14 for engagement by 30 the device for rotatively securing the support for the shoe last in connection with the upper end of the frame. This device comprises a member 15 having one end mounted on a pivot 16 in a slot 17 formed in the tubular body 4. The opposite end of the member 15 is provided 35 with a projecting handle portion 18 for manual engagement to move said member 15 from and into the slot 17. The groove 14 is radially opposite the slot 17 and when 40 the member 15 is in effective position (Figs. 2 and 3) it engages in the groove 14, thereby preventing withdrawal of the rotary shoe support from the tubular frame body 4, while permitting rotation of the shoe support.

45 A shaft 19 extends axially through the body 10. The body 10 is rigidly secured to the shaft 19 by removable set screws 20 which are screwed into holes in the body 10 and have their inner ends abutting and clamping 50 against the shaft 19, thereby to prevent said shaft 19 from turning with respect to the body 10.

The shaft 19 is formed, along one side thereof, with a longitudinal groove or slot 55 21. This slot 21 is parallel with the axis of the shaft 19. A gripper member, comprising an appropriately shaped bar 22, is mounted for longitudinal sliding movements in the groove or slot 21. This gripper member extends through the body 10 which does not in the least interfere with the longitudinal sliding movements of said gripper member. The inner end of the gripper member is formed with a portion 23 that extends 60 radially beyond the surface of the shaft 19

and is also formed with a radially extended arm 24 (Fig. 2). An abutment washer 25 is mounted on the inner end of the shaft 19 and is appropriately recessed so as to be engaged by the parts 23 and 24 of the gripper member 22. Accordingly, the abutment washer 25 can move longitudinally with the gripper member 22, but cannot turn about the axis of the shaft 19 with respect to said gripper member. The abutment washer 25 has, on the side thereof that is toward the body 10, an extended hub portion 26 which is encircled by one end of a spring 27 that bears against the abutment washer 25, while the opposite end of the spring 27 bears against the inner end of the body 10 and is enclosed by a tubular part 28 rigid with and extending from the body 10. Thus, the hub 26 acts to prevent distortion of that portion of the spring 27 which encircles said hub, and the tubular part 28 acts to prevent distortion of that portion of said spring which is enclosed thereby. The abutment washer 25 is spaced from the end of the tubular part 28 so that said washer is capable of movement toward said part 28 from the position in which said washer 25 is yieldingly held by said spring 27.

It is now clear that the body 10 is incapable of longitudinal movements but is capable of turning movements in the tubular supporting body 4; and that the shaft 19 is rigid with the body 10, while the bar 22 is capable of longitudinal movements outwardly from and inwardly to its starting position, which is its effective or gripping position.

A washer 29 (Fig. 2) seats against the outer end of the washer 25 in the gripping position of the slide 22 and abuts against a nut 30 screwed on the threaded end of the shaft 19. A sleeve 31 is mounted for sliding movements in the tubular supporting body 4 and has one end abutting against the washer 29 and enclosing the nut 30. The opposite end of the sleeve 31 has screwed therein a removable abutment bearing 32. This part 32 is removable and replaceable and is also capable of adjustment. So, too, the sleeve 31 may be withdrawn from the tubular support 4 without disturbing or removing the remaining elements that are mounted in said support. The end of the tubular support 4, as shown, is closed by a removable plate 33 secured in place by screws 34.

A bell crank lever is provided to operate the longitudinally movable bar 22. This bell crank lever is mounted on a pivot 35 and has one arm 36 projecting into the tubular body 4 and bearing against the outer end of the abutment 32. The other arm 37 of said bell crank lever has pivoted thereto a depending link 38. A coupling 39 is fastened on the link 38 by a clamping set screw 40. The upper end of a link 41 is clamped in the coupling 39 by a clamping set screw 42.

The lower end of the link 41 is pivoted to an arm 43 rigid on a rock shaft 44 which is supported in a bearing 45 on the base 1 of the machine. A lever 46 has one end attached to the rock shaft 44 and has its other end equipped with a foot pedal 47, thus providing a treadle for turning the shaft 44 in one direction. A spring 48 is arranged in connection with the shaft 44 so as to raise the treadle lever 46 after said lever has been depressed by the foot of the operator of the machine. Thus, I have illustrated an embodiment of means whereby the bell crank arm 36 (Fig. 2) may be operated to move the sliding bar 22 outwardly toward the end of the shaft 19. And, when the treadle is released, the spring 27 acts to move the sliding bar 22 inwardly in a direction away from the outer end of the shaft 19.

The outer end portion 49 of the longitudinally movable bar 22 has an inclined inner wall 50 which operates against a similarly inclined wall 51 which is the bottom wall of the slot 21. These walls 50 and 51 constitute cams whereby the end portion 49 of the bar 22 is moved outwardly and radially automatically and as an incident to inward movement of said bar 22 by the spring 27. That is to say, when the bar 22 is moved outwardly by operation of the bell crank lever 36—37 in opposition to the spring 27, the cams 50 and 51 permit radial inward movement of the end portion 49 of the bar 22. And when the spring 27 acts to move the bar 22 inwardly to its effective or gripping position, the cams 50 and 51 move the end portion 49 of the bar 22 radially outward to gripping position (Fig. 4).

A tapered sleeve 52 constitutes a housing for enclosing the greater portion of the shaft 19 and the bar 22. This sleeve 52 has its inner end engaged in the socket 12 and clamped by the set screw 13. The inside diameter of the outer end portion of the housing 52 is approximately the same as the diameter of the shaft 19 and terminates at a beveled shoulder 53 formed on said shaft 19. When the bar 22 is moved outwardly toward the outer end of the shaft 19, the outer edge of said bar 22 contacts with the inner periphery of the housing 52, with the result that as the outer end portion 49 of the bar 22 moves outwardly it also moves inwardly, due to the relationship of the cams 50 and 51. Thus, when the bar 22 is in its outermost position, the outer edge of the end portion 49 of said bar is approximately even or flush with the peripheral surface of the reduced outer end portion 54 of the shaft 19. But, when the bar 22 is retracted, its outer edge is moved outwardly beyond the peripheral surface of the shaft end 54, which operation is permitted by the tapered arrangement of the housing 52.

The end portion 54 of the shaft 19 has serrations 55 and the outer edge of the end portion 49 of the bar 22 has thereon similar serrations 56.

This form of the invention is constructed and designed specially for use in engaging and supporting shoe lasts within shoes having low uppers. The shoe last 57 shown has in the heel portion thereof a metallic socket 58. The construction and arrangement of the machine is such that when the bar 22 is in its outward or ineffective position and has its outer edge approximately even with the adjacent peripheral surfaces of the shaft end 54, said shaft end 54 and bar end 49 may be inserted into the socket 58. Then, when the treadle lever 46 is released, the spring 27 acts immediately to move the sliding bar 22 longitudinally to its inward position, causing the cam parts 50 and 51 to move radially outward the end portion 49 of said bar 22. This outward radial movement of the end portion 49 causes said end portion 49 and the shaft end 54 to obtain firm gripping engagement with the socket 58. Thus, the shoe last 57 will be held rigidly in connection with this support and the shoe last will hold the shoe upper smooth, so that the shoe may be given the finishing operations. The shaft 19 is freely rotative about its axis and will carry with it the shoe last 57 and thereby the shoe, so that all portions of the shoe may be brought to the position most convenient for operation and treatment by the workman.

The devices shown on Sheet 2 of the drawings comprise an expander for attachment to the machine above described for the purpose of treeing, and expanding and smoothing shoes having high uppers. In order to apply to the machine the expander for shoes having high uppers, it is necessary only to remove the housing 52 and substitute therefor the expander. The parts that are shown on Sheet 2 of the drawings, which are the same as parts shown on Sheet 1 and are above described, have the same reference numerals applied thereto on Sheet 2 as are applied on Sheet 1.

After the housing 52 is removed a tubular element 59 is slipped onto the shaft 19 and inserted in the socket 12. The tube 59 has thereon a circumferential shoulder 60 abutting against the end of the socket 12 and also has thereon a radial projection 61 which engages in a notch 62 in the end of the socket 12 (Figs. 6 and 7). The set screw 13 is then tightened so as to engage the end portion of the tube 59 that is within the socket 12 and thereby prevent outward movement or withdrawal of said tube 59.

An expander member 63 is rigidly secured to the tube 59 and when said tube is mounted on the shaft 19, in the position aforesaid, the outer end of the expander member 63 is ap-

proximately even with the outer edge of the shoulder 53. This expander member 63 is shaped properly to cooperate with the other expander member so as to expand and smooth a high upper of the size for which the expander is intended.

The cooperating expanding member 64 has in its inner end a notch 65. A support 66 is mounted in the notch 65 and has sliding pivotal connection with the expander member 64. The sliding pivotal connection comprises a pin 67 attached to the expander member 64 and extending through a slot 68 in the support 66.

A sleeve 69 is mounted for sliding movements on the tube 59 and has therein a slot 70 which receives the inner end of the support 66. The slot 70 is of sufficient length to permit the sleeve 69 to be moved longitudinally along the tube 59 without interference by the support 66.

A bifurcated lever 71 has pivotal connection 72 with the support 66 and has in the ends of its arms notches 73 for engagement with pins 74 rigid with and projecting radially from opposite sides of the sleeve 69.

A coiled spring 75 supported within the expander member 64 presses against the member 76 mounted on a pivot 76^a on the inner side of the expander member 64. The member 76 has an outwardly bent end 77 adapted to be engaged by a cam 78 on the sleeve 69, when said sleeve 69 is moved outwardly toward the end of the shaft 19 by operation of the lever 71.

The expander member 64 is mounted on the device in position for cooperation with the expander member 63 by engaging the ends of the levers 71 with the diametrically opposite pins 74. An elastic ring 79 is then engaged around the members 63 and 64 and holds said members in the relationship shown in Fig. 6. In that relationship the sleeve 69 is against the shoulder 60. A last-5ed shoe having a high upper may then be treed on the machine. To tree the shoe on the machine the sliding bar 22 is first moved outwardly to permit the socket 80 of the last 81 to be inserted upon the gripping device. When the last is inserted upon the gripping device the treadle 46 is released. When the treadle 46 is released the spring 27 acts to cause the gripper to engage the socket 80 and rigidly hold the last thereon. The high upper of the shoe enclosed a portion of the expander members 63 and 64. A pair of opposite eyelets of the shoe upper are then engaged by hooks 82 connected with one end of a spring 83, the opposite end of which 80 spring is connected with an arm 84 rigid with the expander member 63. The shoe upper is then stretched longitudinally on the expander. Then the lever 71 is operated to move the sleeve 69 outwardly along the tube 59, causing the cam 78 to rub against the in-

clined surface 77 and thereby spread or move the outer end of the expander member 64 which is enclosed within the shoe upper in a direction away from the expander member 63. This is in opposition to the springs 75-79 and also in opposition to the spring 83. In this way the shoe upper is expanded and smoothed. All creases and wrinkles are removed so that the work and operation of finishing the shoe upper is greatly facilitated.

A pin 85 constitutes an abutment for the cam 78 to limit outward movement of the expander member 64 when the sleeve 69 is against the abutment 60.

A highly improved feature of this machine is that construction whereby the lasted shoe is supported upon the rotary support therefor in a relationship in which the rotary support rotates about a horizontal axis and in which the longitudinal axis of the shoe and the last is approximately radial to the horizontal axis, as will be readily understood by reference to Figs. 1 and 6. This permits the shoe to be rotated about the horizontal axis of the support while the longitudinal axis of the lasted shoe remains approximately radial to said horizontal axis.

Heretofore it has been the general practice, and has usually been necessary, to remove the shoes from the original lasts for the finishing operations. By my invention the necessity of removing the shoes from the original lasts is overcome and the finishing operations are more quickly and easily performed while the shoe remains on the original last.

The foregoing description of the machine for use in finishing shoes having low uppers and in finishing shoes having high uppers includes a description of the operation of said machine. The construction and arrangement of the parts comprising the invention may be widely varied without departure from the nature and principle thereof. I contemplate such variation as may be found desirable and do not restrict myself in any unessential particulars, but what I claim and desire to secure by Letters Patent is:—

1. A machine of the character described comprising a hollow support, a member rotatively supported by said support, a shaft rigid in said member, a gripping device at the outer end of said shaft beyond said member for engaging a shoe last, means enclosed in said hollow support for operating said gripping device to gripping position, and means mounted in and guided by said support for operating said gripping device to ineffective position.

2. A treeing jack comprising an approximately horizontal rotary support, a shaft mounted rigidly in and having an end projecting beyond the outer end of said support for engaging in a last socket, a gripper in

connection with said shaft for engaging in and gripping against the wall of a socket in the upper side of a shoe last in a shoe to support the lasted shoe on said shaft for finishing operations, means permitting turning and preventing longitudinal movements of said support, and means for expanding and stretching the shoe upper circumferentially after the last has been gripped by said gripper.

3. A treeing jack comprising a support, a shaft mounted rigidly in and having an end projecting beyond said support for engaging in a last socket, a gripping device for engaging said shaft with the wall of a last socket, means for supporting said gripping device for turning movements in connection with said support, and means in connection with said support for expanding and stretching the shoe upper circumferentially after the last has been completely engaged by said gripping device.

4. A treeing jack comprising a gripping device for engaging in a socket in the upper side of the heel portion of a last in a shoe, automatic means for operating said gripping device to gripping position, manual means for releasing said gripping device, means for supporting said gripping device for turning movements about a horizontal axis, and resilient actuators for expanding and stretching the shoe upper both longitudinally and circumferentially.

5. A treeing jack comprising a gripping device for engaging in a socket in the upper side of the heel portion of a last in a shoe, automatic means for operating said gripping device to gripping position, manual means for releasing said gripping device, means for supporting said gripping device for turning movements about a horizontal axis, mechanism for operating said gripping device to engage and to release the last, and mechanism for expanding and stretching the shoe upper circumferentially after the last has been completely engaged by said gripping device.

6. A machine of the character described comprising a support, a gripping member, means carried by said support for supporting said gripping member for turning movements and preventing longitudinal movements of said gripping member, a cooperating gripping member supported in connection with said first gripping member, means enclosed in said support for moving said cooperating gripping member to gripping position with respect to said first gripping member, in which position said two gripping members are adapted to grip against the wall of a socket in a shoe last, and a lever extending into said support for operating said means and thereby said gripping member to position to release the shoe last.

7. A machine of the character described comprising a support, a gripping member,

means carried by said support for supporting said gripping member for turning movements and preventing longitudinal movements of said gripping member, a cooperating gripping member supported in connection with said first gripping member, means inclosed in said support for moving said cooperating gripping member to gripping position with respect to said first gripping member, in which position said two gripping members are adapted to grip against the wall of a socket in a shoe last, a lever extending into said support for operating said means and thereby said gripping member to position to release the shoe last, and mechanism for expanding and stretching a shoe upper.

8. A machine of the character described comprising a tubular support, a member extending into said support for rotary movements, a shaft attached to said member and projecting beyond the outer end thereof, a gripping device at the outer end of said shaft for engaging and supporting a shoe last, and a device in said tubular support for operating said gripping device.

9. A machine of the character described comprising a tubular support, a member extending into said support for rotary movements, a shaft attached to said member and projecting beyond the outer end thereof, a gripping device at the outer end of said shaft for engaging and supporting a shoe last, a device in said tubular support for operating said gripping device to effective position, and mechanism for operating said gripping device to ineffective position.

10. A machine of the character described comprising a tubular support, a member projecting into said support for rotary movements, a shaft attached to said member and extending into said tubular support and projecting outwardly beyond said member, a gripping device at the outer end of said shaft for engaging and supporting a shoe last, an actuator enclosed within said tubular support for actuating said gripping device to gripping position and permitting movement of said gripping device to released position, a lever, mechanism for operating said lever, and means operated by said lever for moving said gripping device to released position.

11. A machine of the character described comprising a hollow support, a rotary member carried by said support, a gripping device supported by said rotary member for engaging and supporting a shoe last, an actuator enclosed in said support for actuating said gripping device to gripping position and permitting movement of said gripping devices to released position, and mechanism for operating said gripping device to released position in opposition to said actuator.

12. A machine of the character described comprising a rigid vertical support, a sepa-

rate horizontal support, means for holding said horizontal support rigid with the upper end of said vertical support in selected vertical and laterally extended positions, and 5 mechanism carried by said horizontal support for engaging the last in a lasted shoe and supporting the lasted shoe for rotation about a horizontal axis in a position in which the longitudinal axis of the shoe is approximately radial to said horizontal axis.

13. A machine of the character described comprising a hollow support, an additional support carried by said hollow support for rotation about a horizontal axis, a gripping 15 element carried by said additional support for engaging the last of a lasted shoe and supporting the lasted shoe for rotation about a horizontal axis in a relationship in which the longitudinal axis of the shoe is approximately radial to said horizontal axis, a second gripping element cooperating with said first gripping element for engaging and holding the last in connection therewith, means for operating said second gripping element to 20 engage and to release the last, and mechanism for expanding and stretching circumferentially and longitudinally the shoe upper.

14. A machine of the character described comprising mechanism cooperating with the 30 original last on which a shoe is lasted and while the shoe is on the last for supporting the shoe for rotation in a plane in which the longitudinal axis of the shoe is approximately radial to the horizontal axis about which 35 the shoe is rotated, a device for stretching the shoe upper longitudinally, and manually operative means for expanding the shoe upper circumferentially after the last has been connected with said mechanism.

15. An expander for a shoe upper comprising resilient means for stretching the shoe upper longitudinally, and a manually operative device for expanding the shoe upper circumferentially.

16. A treeing jack for treeing shoes for finishing operations comprising a support for supporting a last on which the shoe is mounted, a pair of expander members, resilient means for moving one of said expander members in a direction away from the other to expand the shoe upper, and a manual device for causing said resilient means to move said expander member as aforesaid.

17. A machine of the character described 55 comprising a rotary support for a shoe, an expander member rigid with said support and arranged to extend into the shoe upper, a cooperating expander member pivotally carried by said support and arranged to extend 60 into the shoe upper, resilient means for moving said cooperating expander member away from said first expander member to expand the shoe upper, and means for causing said resilient means to operate.

18. A machine of the character described

comprising a stationary support, a rotary support extending into and supported by said stationary support, cooperating gripping elements supported by and projecting beyond the end of said rotary support for 70 engaging the original last on which a shoe is lasted to support the shoe for rotation in a plane in which the longitudinal axis of the shoe is approximately radial to the axis about which the shoe is rotated, a resilient actuator enclosed within said stationary support for holding said gripping elements in effective position and permitting movement of said gripping elements to ineffective position, a bell crank lever, means for pivotally supporting said bell crank lever in position in which one arm extends into said stationary support and the other arm extends out of said stationary support, means operative by 80 said bell crank lever for moving one of said gripping elements to ineffective position with respect to the other gripping element, and means for operating said bell crank lever.

19. A machine of the character described comprising a stationary support, a rotary support extending into and supported by said stationary support, cooperating gripping elements supported by and projecting beyond the end of said rotary support for 90 engaging the original last on which a shoe is lasted to support the shoe for rotation in a plane in which the longitudinal axis of the shoe is approximately radial to the axis about which the shoe is rotated, a resilient actuator enclosed within said stationary support for 95 holding said gripping elements in effective position and permitting movement of said gripping elements to ineffective position, a bell crank lever, means for pivotally supporting said bell crank lever in position in which one arm extends into said stationary support and the other arm extends out of said stationary support, means operative by 100 said bell crank lever for moving one of said gripping elements to ineffective position with respect to the other gripping element, and means for operating said bell crank lever.

20. A machine of the character described comprising a stationary support, a rotary support carried by said stationary support, a shaft for one end mounted in said rotary 120 support and having the opposite end adapted to engage a shoe last, a gripping member in said shaft and cooperating with said last named end of said shaft to obtain gripping engagement with the shoe last, a sleeve enclosing a portion of said shaft beyond said rotary support, detachable means holding said sleeve in connection with said rotary support and terminating out of engagement with 125 a last engaged by said gripping element.

21. A machine of the character described comprising a stationary support, a rotary support carried by and having one end projecting beyond said stationary support to engage in a socket in a shoe last, a gripping member extending along said rotary support and arranged to extend into the socket in the shoe last and cooperate with said end of said rotary support to support the shoe last, a lever for moving said gripping member to position for extension into the socket, automatic means operating after release of said lever to move said gripping device to engage the socket of the shoe last and hold the shoe last on said rotary support, expanding devices, a support for said expanding devices, and detachable means for securing said last named support in connection with said rotary support.
